DESIGN FOR FRINGE.

Design No. 13,717, dated March 13, 1883.

UNITED STATES PATENT OFFICE.

JOSEPH GOODMAN, OF PHILADELPHIA, PENNSYLVANIA, ASSIGNOR TO E. H. GODSHALK, OF SAME PLACE.

DESIGN FOR FRINGE.

SPECIFICATION forming part of Design No. 13,717, dated March 13, 1883.

Application filed January 10, 1883. Term of patent 3½ years.

To all whom it may concern:

Be it known that I, JOSEPH GOODMAN, a citizen of the United States, residing in the city and county of Philadelphia, State of Pennsylvania, have invented and produced a new and original Design for Fringe, of which the following is a specification, reference being had to the accompanying photographic illustration, forming part thereof.

10 The leading feature of my design for fringe consists of pendants of quadrilateral form.

A represents the pendants, which are of quadrilateral form, and connected with a suitable head.

B represents balls, tufts, or swells, which 15 may be on one or both ends of the pendants.

I claim—

1. The design for fringe, having pendants of quadrilateral form, substantially as above described and shown. 20

2. The design for fringe, having pendants of quadrilateral form, with balls or swells at the ends thereof, substantially as above described and shown.

JOSEPH GOODMAN.
